GAS MIXER

Jesse E. Shull, Alpena, S. Dak.

Application November 7, 1935, Serial No. 48,743
Renewed May 5, 1937

2 Claims. (Cl. 48—180)

The invention relates to devices for application to the intake manifolds of internal combustion engines to thoroughly mix the gasoline vapor and air after leaving the carburetor and before entering the engine, and has for its principal object the provision of a plate adapted to be installed in the intake manifold, and provided with a plurality of openings, and having mounted on said plate and in line with said openings a plurality of independently rotatable agitating devices, consisting of a hub-like sleeve in each instance having radially extending blades, the blades being inclined so that the agitating members are impelled by the vapor and air engaging 5 said blades to rotate the members and thereby agitate the vapor and air to thoroughly mix the vapor and air before entering the cylinders of the engine.

A further object of the invention is provision 20 of a device of the character stated, in which the rotating members are of different diameters, the smallest diameter member being nearest to the carburetor, and the other blades of increasing diameter being arranged farther from the carburetor.

A further object of the invention is the provision of means for mounting the mixing members consisting of the provision of spindles mounted on the plate to receive the sleeves or hubs of 30 the mixing members, the blades being mounted on the sleeves or hubs adjacent to the outer ends thereof, and thus provide for spacing the blades of the adjacent members; the inner edges of the sleeves having circumferential flanges that ride 35 on the adjacent edges of the supporting sleeve, such flanges providing baffles at the inner ends of the blades.

The invention will be described in detail herein-after and will be found illustrated in accompanying drawing, in which

Figure 1 is a fragmentary view of a carburetor and intake manifold, shown partly in section, with the improved gas mixer shown in position therein,

Figure 2 is a plan view of the gas mixer,

Figure 3 is a transverse sectional view on a plane indicated by line 3—3 of Figure 2, and

Figure 4 is a fragmentary sectional view on a plane indicated by line 4—4 of Figure 3.

50 In the drawing similar reference characters are used to designate corresponding parts on all of the views.

In Figure 1 the improved gas mixer is shown as applied to an intake manifold 10 of an internal combustion engine, 10a indicating the casing of

a carburetor. The improved gas mixer consists of a plate 11 which is secured in the intake manifold between the flange 12 and the carburetor at the intake manifold 10, by means of bolts or screws 13 secured to flanges 14 and 15 on the 5 nipple 12 and the intake manifold 10, respectively.

The plate 11 is provided with a plurality of openings 16, the number selected for illustration being two, and each of said openings is provided with a diametrically disposed cross bar 17 to 10 support a spindle 18. Mounted on each of the spindles 18 is a plurality of rotatable mixing members, or fans, or impellers, each of said members having a central sleeve-like hub 19 and a plurality of blades extend radially from said 15 sleeve-like hub 19, the blades 20 of the members adjacent to the plate 11 being, as shown, shortest of the blades of the different members, the blades of the next member, designated 21, being slightly longer than the blades 20, and the blades of the 20 outer member being longer than the blades 21. By this arrangement it will be apparent that all the body of vapor and air passing through the openings 16 and into contact with the members will be thoroughly agitated and mixed before 25 passing out of the influence of the mixing members.

The blades 20, 21, and 22 are inclined laterally, so that they act as impellers and are rotated by the contact of the air and vapor there- 30 with. Furthermore, the blades, as shown, are arranged adjacent to the upper or outer edges of the sleeve 19, the longer lower portion of the sleeve providing for spacing the blades of adjacent members from one another, and further- 35 more, the lower edges of the sleeves are provided with circumferential flanges 23 that ride on the adjacent sleeve, and said flanges have the function of baffles to keep the air and vapor from following up the surfaces of the sleeves, such 40 baffles serving to throw the air and vapor outwardly into the vortex of the blade.

I claim as my invention:

1. A gasoline vapor and air mixer, comprising 45 a plate adapted to be mounted in an intake manifold of an internal combustion engine and having a plurality of openings therein, spindles mounted on said plate and perpendicular thereto, one each of said spindles being mounted concentric with each of said openings, a plurality of independently rotatable sleeves mounted on each spindle, said sleeves being superposed, a plurality of laterally inclined blades extending radially 50 from each of said sleeves, said blades being spaced 55 from each of said sleeves, said blades being spaced

and of increasing length, and the blade nearest the plate being the shortest.

- 5 2. A gasoline vapor and air mixer, comprising a plate adapted to be mounted in an intake manifold of an internal combustion engine and having a plurality of openings therein, spindles mounted on said plate and perpendicular thereto, one each of said spindles being mounted concentric with each of said openings, a plurality of 10 superposed, independently rotatable sleeves mounted on each of said spindles, a plurality of

laterally inclined blades extending radially from each of said sleeves and vertically spaced, said blades being adjacent to the ends of the sleeves remote from the plate, the other ends of each sleeve having a circumferential flange to provide a baffle for vapor and air at the inner ends of the blades, the blades being of increasing length on the respective sleeves, and the blades on the sleeve nearest the plate being the shortest.

JESSE E. SHULL.
